BRASSIÈRE

Mary Park, Chicago, and Marie Martin, Riverside,
Ill., assignors to The H. W. Gossard Company,
Chicago, Ill., a corporation of Delaware

Application March 30, 1934, Serial No. 718,174

1 Claim. (Cl. 2—42)

This invention relates to brassières and has for its object to provide a simple inexpensive garment of this type which is adaptable to various sizes and may be adjusted and worn in several 5 different ways, as with high or low cut gowns, serving in all cases to elevate the busts to a high and youthful position heretofore obtainable only with individual high and low back brassières which have always formed a necessary part of 10 the average woman's wardrobe.

The invention will be described in connection with a short brassière, but it is equally applicable to combinations, long brassières, and other similar garments.

15 In the accompanying drawing showing the preferred form of the invention:

Fig. 1 is a rear perspective view;

Figs. 2 and 3 are front and rear views of a torso wearing the brassière in the form of a 20 halter;

Figs. 4 and 5 are front and rear views showing the garment converted into a two-strap brassière; and

25 Fig. 6 is a rear view showing the straps crossed at the back.

The brassière shown in the drawing comprises a front portion made of light netting constituting individual bust pockets of conical contour. In the form shown, the bust pockets comprise 30 substantially triangular strips of netting 1 and 2 having a common base line and having portions extending from their centers to their adjacent apices cut out and replaced by gores of netting 3 and 4 in the general shape of acute-angle triangles of such size as to give the pockets the desired fullness and conical contour.

The respective sections 1, 3 and 2, 4 are cut and stitched together in such a way as to provide flexibility in the general direction of the 40 arrows in Fig. 1, the object being to gather and mold the busts to a conical contour when the lower edge of the brassière is fastened about the body and the upper apices of the bust pockets are elevated by the shoulder strap or straps as 45 hereinafter described.

Suitable inelastic bindings 5 and 6 reinforce the outer edges of the bust pockets, these bindings crossing at the lower overlapping apices of the pockets and forming a small relatively stiff central triangle 7 which is 50 adapted to lie between the busts adjacent the breast bone. The lower edge of the brassière is bound with a strip of netting 8 which is doubled over and has its upper edges turned in and secured to the lower edge of the brassière by 55 stitches 9. The outer ends of the brassière are

connected by an elastic back strap 10 which is detachably secured at one end by a hook and eye, button, snap or other fastening means 12.

The brassière has elastic shoulder straps 13 and 14, one of which may be permanently connected to the upper edge of one bust pocket and the other of which is completely detachable from the garment. In the form shown, strap 13 has one end secured to bust pocket 1 at point 15 and is provided at the other end with fastening means 10 such as hook 16 adapted to be selectively engaged with eye 17 at the upper edge of bust pocket 2 or with either of spaced eyes 18 and 19 adjacent the respective ends of back strap 10. Strap 14 has end hooks 20 and 21 for connection to eye 17 and to either of eyes 18 or 19 as hereinafter described. A broad ribbon 22 is slidably mounted on back strap 10 and carries a depending loop or other fastening means 23 for connection to a girdle or other lower garment. 20

Throughout this application where detachable hook and eye is shown and mentioned, it will be understood that other equivalent fastenings such as buttons and buttonholes, snaps, etc., may be used. 25

To make a halter, strap 13 is drawn around the neck and fastened by engaging hook 16 in eye 17 as in Figs. 2 and 3, strap 14 not being used in this embodiment. To make a conventional two-strap brassière, strap 13 is passed over the adjacent shoulder and hook 16 engaged with eye 18, while hook 20 of detachable strap 14 is engaged with eye 17 at the upper edge of bust pocket 2 and hook 21 is engaged with eye 19 of back strap 10, the straps 13 and 14 in such case providing 30 substantially vertical lines of support. When worn with low back evening gowns, etc., loop 23 is attached to a garter belt, girdle or the like, pulling back strap 10 down and providing a completely backless brassière while exerting an up- 35 lift tension on the bust pockets. To convert the garment into a cross-strap brassière, the straps are crossed as in Fig. 6 and fastened by engaging hook 16 of strap 13 in eye 19 and hook 21 of strap 14 in eye 18, providing diagonal or cross tension which is desirable in some cases to prevent straps 13 and 14 from slipping off the shoulder. In this form the garment may also be worn with low back evening gowns by fastening loop 23 to a girdle or the like, the resulting tension pulling 50 the shoulder straps down and increasing the uplift effect upon the bust pockets.

Thus the invention provides a very simple convertible brassière which serves equally well for sport or general wear or as an evening garment 55

for use with low back gowns, the elasticity of the parts furthermore adapting each garment to figures of varying size.

The invention claimed is:

- 5 A brassière comprising connected front portions constituting individual bust pockets, an elastic back strap connecting the outer ends of said bust pockets for fastening said brassière about the body, and means for elevating said bust
10 pockets comprising an elastic shoulder strap connected to the upper edge of one of said bust pockets and of length such as to pass around the neck and detachably connect to the upper edge of the second bust pocket or to pass over the shoul-

der and detachably connect to said back strap, means for selectively connecting said shoulder strap to said second bust pocket or to any of a plurality of spaced points on said back strap, a second elastic shoulder strap having means for detachably connecting to the upper edge of said second bust pocket and any of said spaced points on said back strap, and a member slidably mounted on said back strap having means for fastening to a girdle or the like to exert a downward tension on said straps and an increased uplift on said bust pockets. 5 10
